UNITED STATES PATENT OFFICE.

FRIEDRICH RUDOLF METZ AND EMIL HOERNSTEIN, OF MÖDLING, NEAR VIENNA,
AUSTRIA-HUNGARY, ASSIGNEES TO THE FIRM OF AKTIENGESELLSCHAFT FÜR
PATENTIERTE KORKSTEINFABRIKATION UND KORKSTEIN-BAUTEN VORMALS
KLEINER & BOKMAYER, OF VIENNA, AUSTRIA-HUNGARY.

MOLD FOR FORMING BLOCKS OF CORK.

1,139,699.

Specification of Letters Patent. Patented May 18, 1915.

Original application filed May 14, 1912, Serial No. 697,313. Divided and this application filed July 3, 1913.
Serial No. 777,140.

To all whom it may concern:

Be it known that we, FRIEDRICH RUDOLF METZ and Dr. EMIL HOERNSTEIN, subjects of the Emperor of Austria-Hungary, residing 5 at Mödling, near Vienna, in the Province of Lower Austria and Empire of Austria-Hungary, have invented certain new and useful Improvements in Molds for Forming Blocks of Cork, of which the following is a specification.

The subject matter of this invention is a mold for manufacturing insulating blocks or the like of cork, *i. e.* made of comminuted cork with a binding medium, *e. g.* pitch. If 15 the mixture of cork particles and pitch is hardened within the mold the block adheres to the walls of such mold in such a manner, that it is impossible to remove the block from the mold without destroying the 20 block.

According to this invention the knock-down or collapsible mold, consisting of a frame, covered on its two opposite sides by removable sieves or the like previous to the 25 binding material, contains on the inner surface of the frame removable linings of a flexible or elastic material *e. g.* of steel strips, sieves or the like. These sieves and linings adhere to the block formed in the 30 mold and may be withdrawn together with the hardened block from the frame after the covering sieves having been pulled off and thereafter these linings are pulled off from the block. The frame itself may also be 35 knockdown or collapsible, in order to facilitate the removing of the hardened block together with the linings.

A mode of construction of the mold is shown in the accompanying drawing in 40 which—

Figure 1 is an elevation, partly dismantled. Fig. 2 is a cross section, and Fig. 3 shows a view of a sieve supporting frame.

The mold consists of a frame which may 45 be preferably knockdown or collapsible, of two sheets covering the two opposite open sides of the frame and of two frames for fixing and supporting the said sheets to the first named frame. This latter frame consists of two parts 1 and 2, provided with 50 hooks 3 and 4 engaging with bolts 5 and 6 of the part 7, so that the parts 1 and 2 may

be turned around the bolts 5 and 6 and also removed from the part 7 at will. The free ends of the parts 1 and 2 are kept together 55 by the part 8, when the mold is closed.

The inner surfaces of the parts 1, 2, 7 and 8 are lined with strips or linings 9, 10, 11 and 12 of a flexible material, *e. g.* with steel strips or metal sieves or the like. 60

The open opposite sides of the frame 1, 2, 7 and 8 are covered by flexible perforated metal sheets or sieves 13 and 14 and these sheets or sieves are supported by frames 15 and 16 to be fixed to the frame 1, 2, 7, 8 65 by any suitable means, as *e. g.* by bolts or the like, means which allow an easy connecting and disconnecting of the frames.

The handles 17, 18, 19 and 20 facilitate carrying the mold and hanging it on an 70 elevator, in order to dip the mold into a bath of a liquefied binding material, *e. g.* pitch and to remove it again therefrom.

After the mold is assembled without the part 8, cork particles 21 are filled into the 75 free space between the frame 1, 2, 7 and the sheets 13 and 14. Also reinforcements of iron, wood or the like for the block to be formed may be put in together with the cork particles. Then the mold is closed by 80 the part 8 and the whole is dipped into the bath of a liquefied binding material, which may enter into the interior of the mold and into the interstices between the cork particles through the perforations of 85 the sheets 13 and 14. After a short period the mold is raised from the bath and remains closed till the binding material is hardened. Then the mold is dismantled by removing 90 subsequently the parts 15, 16, 8, 1, 2 and 7 90 whereupon the sheets 13 and 14 and also the linings 9, 10, 11 and 12 adhering to the block formed in the mold are pulled off from the block and the process is completed. The mold may be assembled again, charged 95 with cork and the process repeated.

One of the sheets 13 and 14 may be imperforate, if desired.

This application is filed as a divisional application under our pending parent application Serial No. 697,313, filed May 14, 1912.

Having now particularly described and ascertained our invention, what we claim is:

A knockdown or collapsible mold for forming blocks composed of comminuted cork and an adhesive binding material, said mold comprising walls readily separable one from another; flexible lining strips for lining the inner surfaces of said walls, said flexible lining strips being susceptible of being readily torn from the hardened molded block; and a perforate wall through the

perforations in which flows the binding material into and from the mold.

In testimony whereof we affix our signatures in presence of two witnesses.

FRIEDRICH RUDOLF METZ.

DR. EMIL HORNSTEIN.
